UNITED STATES PATENT OFFICE

CHARLES E. SORENSEN, OF DETROIT, MICHIGAN, ASSIGNOR TO FORD MOTOR COMPANY,
OF FORDSON, MICHIGAN, A CORPORATION OF DELAWARE

CONVEYER

Application filed February 18, 1929. Serial No. 341,021.

The object of my invention is to provide a conveyer of simple, durable, and inexpensive construction.

A further object of my invention is to provide a conveyer which is adapted to transfer chips and cuttings from the various machines used in a manufacturing plant, and which is also adapted to transfer the cutting fluid used with the machines so that the cost of disposing of these two materials will be reduced to a minimum.

In the modern manufacturing plant, one of the major expenses incurred is the cost of carrying away the chips produced by the various machines used. A further expense is incurred due to the enormous amount of piping required to carry the cutting fluid, normally soda water, which is used to cool the machine tools, to central settling tanks where it is again piped to the various machines.

It has become general practice in large manufacturing plants to pipe the cutting fluid, normally soda water, under pressure to each individual machine by overhead piping where the fluid is directed through nozzles onto the cutting tools. This is comparatively easy to accomplish as the pipes may be relatively small for a great quantity of the cutting fluid due to the pressure usually placed on the system.

The returning of this water from the machines to a central settling tank is, however, a much more difficult matter as the water must flow by gravity from each machine. There is further, a considerable quantity of chips and other material in the soda water which makes its return transfer extremely difficult. The method commonly used for the return piping is to place holes in the floor of the building at each machine and to extend a large pipe therethrough which connects with a large main pipe suspended from the ceiling of the floor below and which conveys the return water to a main settling tank. It will readily be seen that it is very expensive to install this return system, due to the reinforced construction of the floors in the modern manufacturing building and that when this system is once installed it

does not lend itself to changes which may be made necessary in the future. Further, these return mains from time to time become clogged with chips and the like and considerable expense is necessary to clean these lines out and insure continuous operation of the system.

Still a further object of my invention is to provide a chip conveyer which may be installed in an existing building without extensive alterations being necessary to the building.

Still a further object of my invention is to provide a chip conveyer which may be manufactured in units and adapted to be set up in any ordinary manufacturing space and to which additions may be easily made when necessary.

A further object of my invention is to provide a chip conveyer which will receive the chips and soda water from the machines and which will convey the chips in one direction while the water is conveyed in the opposite direction.

Still a further object of my invention is to provide a chip conveyer wherein the upper portion of the conveyer is utilized to carry chips from machines and the bottom portion is used as a trough to convey the cutting fluid and thereby eliminate the return piping ordinarily necessary for said water. In my improved system the top conveyer line acts as a sieve through which the soda water filters to the bottom of the unit and is there carried in the opposite direction by the return conveyer line, together with any chips which may filter through with the water. The system is thus kept free from chips and suitable for continuous operation.

Still a further object of my invention is to provide a conveyer system in which each conveyer apron is fastened to the side chains without special attachment, the chain pin being used for this attachment.

Still a further object of my invention is to provide a novel conveyer layout in a manufacturing plant, which will eliminate the manual handling of all surplus materials connected with the manufacturing machines,

and which will provide ample aisle space for each machine for bringing the rough stock to the machine and returning the finished product. In my improved layout I provide a trunk conveyer into which branch conveyer lines discharge, the branch conveyer lines having machines placed on each side thereof and into which the chips from the machine together with the soda water is run; the whole arrangement being so that ample aisle space is provided between the rows of machines.

With these and other objects in view my invention consists in the arrangement, combination, and construction of the various parts of my improved device, as described in the specification, claimed in the claim, and illustrated in the accompanying drawings in which:

20 Figure 1 shows a plan view of my improved device in which a main conveyer system, branch lines and machines are shown.

25 Figure 2 shows a view of the junction of a branch line with the main conveyer line, parts being broken away to better illustrate the construction.

30 Figure 3 shows a vertical, central, longitudinal, sectional view taken through the conveyer system, illustrating the construction of the conveyer trays.

Figure 4 shows a vertical, sectional view taken on the line 4—4 of Figure 3.

35 Figure 5 shows a sectional view taken on the line 5—5 of Figure 3.

Referring to the accompanying drawings, I have used the reference numeral 10 to indicate generally a trunk conveyer line having branch lines 11 extending from either side thereof. A number of machines 12 shown in dotted lines, are placed on each side of each conveyer lines 11, and have suitable means for discharging the chips and soda water used with each machine into the adjacent conveyer line 11.

40 Main aisleways 13 run parallel to an alternate with the trunk conveyer line 10, and branch aisleways 14 extend from the main aisleways parallel to and alternate with the branch conveyer lines 11.

It may be seen from Figure 1, that ample aisle space is provided adjacent to each machine and that the conveyer system, even though placed directly on the floor, in no way interferes with the movement of supplies and transfer of the finished pieces from the machines. The conveyer system forms a network of transportation members which are used exclusively to carry the chips and soda water from the machines, while the alternate aisleways are used exclusively to carry the finished parts and stock to and from these machines.

45 The trunk conveyer line 10 may extend out from the building through any suitable

opening and discharge into a chip receiving car 40.

From the foregoing it may be seen that each machine discharges its chips and soda water, used with the cutting tools, into the adjacent branch conveyer 11 which carries the chips to the trunk conveyer 10 and discharges them therein. The trunk conveyer in turn conveys the chips to the car 39. The soda water is not carried with the chips to the trunk conveyer but filters through openings in the conveyer trays to the bottom of the conveyer unit and it there is carried away from the trunk conveyer to the opposite end of the branch line by the returning trays, and is drawn from the outer end of each branch conveyer to a main settling tank.

The conveyer proper consists of a channel shaped trough 15 which extends the length of the conveyer system. Angle irons 16 are secured to the inside face of the upright members of the trough 15 about midway thereof. Splash plates 17 are secured to the top edges of the channel sides of trough 15 and are reinforced by suitable members 18, the plates 17 and reinforcement 18 extending the full length of the conveyer. At intervals of four or five feet braces 19 are fastened to the lower edge of the angles 16 and form a tie rod which prevents the trough 15 from expanding or collapsing due to the strain of the conveyer system placed therein.

50 The extending arms 20 of angle 16 project inwardly, and a suitable track 21 is secured to the upper face of these arms. A similar track 22 is secured in the bottom of the trough 15 and is used for the return conveyer track.

The foregoing description is intended to bring out a construction having a trough extending the full length of the conveyer and in which two tracks are placed one above the other and which has suitable splash guard members extending over the top thereof to guide the incoming material to the central part of the trough.

55 The conveyer chain and tray assembly consists of a series of duplicate trays secured to each other at each end and fastened to the chains at each side of each tray. The trays are also designed so that material will not be able to collect in between the trays.

60 The tray 23 is formed from sheet metal into a shallow rectangular pan having integral complementary guard portions at each end thereof. The rear wall 24 of the tray is curved so as to extend over the forward wall 25 of the following tray so that there is no opening for chips to collect between the trays. The sidewalls 26 of the trays 23 extend beyond the tray proper and have an opening in each end of each wall through which the driving chain pins extend. A

slot 27 is formed in each corner of each tray, the purpose of this slot being to allow the soda water to filter therethrough and enter the bottom of the tank 15.

5 The driving chains consist of outer links 28 which are alternated with inner links 29 and held together by pins 30. These pins 30 are provided with a flat section 31 adjacent to their outer end which co-acts with 10 a correspondingly shaped opening 32 in the outer links 28. This flat section restrains the pin from rotating relative to this link. The pin is further held from axial movement relative to the link by means of a cotter key 33.

A bushing 34 is rotatably mounted on the pins 30 between the inner links 29 and is free to rotate relative to this pin 30 but is restrained from rotation relative to the links 20 29 by a flat portion on the bushing similar to portion 31. A roller 35 is rotatably mounted on the outside of the bushing 34 and is used to support the chains and trays on the tracks 21 and 22. The adjacent openings 25 in the extending portions of side walls 26 are pivotally connected by the inner ends of the pins 30.

From the foregoing description, it may be seen that the trays 23 are flexibly secured 30 together by the inner ends of pins 30 and that these pins are restrained from rotation relative to one of the trays 23 by reason of their being non-rotatably mounted in the links 28. It is important that pin 30 is held from rotation as otherwise the openings in the sidewalls would be excessively enlarged in a short time and cause failure of the conveyer. It is likewise important that the bushing 34 be held from rotation 35 relative to the links 29 to thereby prevent elongation of the openings in the ends of these links. Practically all the friction of the rollers 35 is taken on the outer wall of the bushing 34 which is amply proportioned 40 to take this load.

At spaced intervals along the conveyer, or as in the construction shown, at each fourth tray, the right and left hand link pins 30 are formed of a continuous rod which extends the full width of the conveyer to thereby relieve the trays of any bending action 45 due to the load therein and to keep the chains uniformly spaced independently of the conveyor trays.

50 Figure 2 shows a junction of one of the branch conveyer lines 11 with the trunk line 10 and illustrates how the branch line 11 is elevated and driven at this end where it joins the trunk conveyer 10. This view 55 also illustrates the construction whereby both the conveyers are placed directly on the floor and still discharge from one to the other.

55 A sprocket 36 is driven through a suitable reduction gearing by means of an electric

motor 37 to thereby drive the conveyer. A guide sprocket 38 is mounted in line with the top conveyer chain to insure a horizontal pull on the conveyer. The chain is, of course, in the form of a continuous belt 70 and a suitable sprocket on the outer end of the conveyer is provided in the conventional manner. There are many methods applicable to the driving of the conveyer system, any one of which may be used in this 75 installation, and I have merely shown this method as one of the many possible ways of driving the conveyer.

The trough 15 is provided at the extreme outer end with an opening 39 in the bottom 80 part which forms an outlet for the soda water. The soda water is then run from the openings 39 to a main settling tank through suitable piping.

It will be understood that this conveyer 85 construction is such that material conveyers can be placed above these chip conveyers for the purpose of carrying materials to and from the workmen.

Among the many advantages arising from 90 the use of my improved conveying system it should be recalled that I have provided a conveying system which may be installed in any existing building without expensive alterations to the building. Further, the system is so constructed that additions may be made at any time without stopping or changing the existing conveyer system or in any 95 way interfering with its operation. Further, the system is so arranged that ample 100 aisle space is provided between the machines, and the system is flexible enough to permit machines of any size or proportion which may be necessary to the manufacturing to be used.

105 A further advantage results in that the chips are carried in one direction to a trunk line conveyer and the soda water deposited in the conveyer with the chips is carried in the opposite direction to a settling tank, 110 thereby eliminating to a large extent the complicated piping necessary to carry the soda water. Further, the conveyer is constructed from a series of duplicate parts 115 which make the repairing or additions thereto a relatively simple matter. Further, the trays are secured to the side chains of a conveyer without any special attachments or fixtures which considerably reduces the cost of the conveyer and produces a longer life 120 construction.

Some changes may be made in the arrangement, construction and combination of my improved device and it is my intention to cover by my claim such changes as may reasonably be included within the scope thereof.

I claim as my invention:

In a portable conveyer adapted to separate solids from liquids, a channel shaped 130

trough formed from a single sheet of metal the edges of which are bent upwardly to form side members integral with the bottom of the trough, a pair of longitudinally extending angle irons fixedly secured within the trough to the intermediate portions of the side members, a rail secured to the upper face of each of the inwardly projecting legs of said angles to thereby form a conveyer track, a plurality of transverse braces extending between each of said angle irons and secured to the lower faces thereof, a second pair of rails extending within said trough and secured to the bottom thereof to form a return track below the first mentioned track, a continuous conveyer disposed within said trough having perforated trays thereon adapted to retain solid material and allow liquids to filter therethrough, said conveyer having a plurality of rollers secured along the edges thereof adapted to operate upon said tracks, an inwardly and downwardly inclined plate secured to each upper edge of said side members, whereby liquid deposited into said trough will be conducted into the perforated trays from which it will filter therethrough into the liquid-tight trough, and an outlet pipe for said liquid disposed in one end of said trough.

28 February 14, 1929.

CHAS. E. SORENSEN.
